UNITED STATES PATENT OFFICE

JOHN S. BARNES AND JACOB A. SANDS, OF ANN ARBOR, MICHIGAN

WINDOW SCREEN

Application filed February 5, 1931. Serial No. 513,651.

Our invention relates to an improvement in window screens shown in the accompanying drawings and more particularly described in the following specification and 5 claims.

One object of the present invention is to construct a window screen embodying a metallic frame, with a flange adapted to overlap the outer marginal edge of the window 10 casing to insure a sealing joint between the window casing and the screen frame, whereby the "opening" bounded by the frame supporting the screen wire may be substantially the same as the "opening" bounded by the 15 window casing thereby providing for a maximum circulation of air through the window—the "opening" not being contracted by the screen frame, as in the ordinary type of window screen construction.

A further advantage gained by constructing the screen frame with a relatively broad flange is that it not only insures a tight joint between the screen and the window casing, but it also provides for considerable latitude 20 in fitting the screen to window openings, which frequently vary considerably,—especially in old houses.

A further object of the invention consists in the means employed to lock the frame to 25 the window casing, thereby insuring a close joint between the screen frame and the window casing and thus overcoming any tendency of the screen to "rattle" due to wind pressure.

A further object of the invention is the reinforcing strips, extending transversely, midway between the top and bottom of the screen frame, between which the wire screen extends and to which it is secured by removable bolts to permit ready renewal of the wire screen when necessary.

A further object of the invention is the means provided whereby an old wire screen may be readily removed for replacement 45 whenever necessary.

A further object of the invention is to provide means whereby the screen frame may be swung outwardly for removal, and for washing the windows as required.

A further object of the invention is the

means employed for hanging a "half-screen" to insure a sealing fit with the upper sash frame.

A further object of the invention is the locking bar or flat wire employed to secure 55 the marginal edge of the screen wire in the grooves formed for its reception in the frame,—and whereby the screen wire is brought under tension,—also the means for securing said flat locking wire in the groove, 60 and means whereby said locking wire may be readily removed when necessary to replace the screen wire.

A further object of the invention is its 65 simplicity and rigidity of construction, also its low manufacturing cost;—the bar forming the inclosing frame being mitered and bent while cold to form the corners of the frame, or it may be divided at the corners 70 and welded together as otherwise indicated.

With the foregoing and other objects in view which will appear as the description proceeds, the invention further resides in the combination and arrangement of parts 75 and in the details of construction hereinafter described and claimed, it being understood that changes may be made in the precise embodiment of the invention herein shown without departing from the spirit of the same.

In the drawings accompanying this specification:

Figure 1 is a fragmentary perspective view 85 of the wall of a building, as seen from the outside of the building, showing a window opening,—the casing for the window sash, and a fragment of the window screen lodged in the opening, with the projecting flanges of the screen frame overlapping the outer wall of the window casing.

Figure 2 is a perspective view of the screen suspended from hooks attached to the window casing,—a fragment of the latter being shown.

Figure 3 is a fragmentary perspective view 95 of the lower portion of the window screen, viewed from the inside of the building, showing a swinging latch having a cam-shaped end provided with a cutting edge, adapted when manually actuated to force its away into 100

the wood of the window casing to secure the screen thereto.

Figure 4 is a fragmentary perspective view of an upper and lower window sash in closed relation, showing a fragment of a "half" window screen, slidably supported in a grooved rail attached to the window casing, said screen frame being fitted with a projecting angle-shaped plate welded to the screen frame 10 to close the opening between the screen and the lower horizontal portion of the upper sash frame.

Figure 5 is a fragmentary detail of the bar forming the inclosing frame of the screen, with a V-shaped notch cut therethrough, preparatory to bending the bar at that point to 15 form a corner of the frame.

Figure 6 is a fragmentary perspective view of the bar shown in Figure 5 bent to form 20 a right-angle, or a corner of the frame.

Figure 7 is a perspective view of the bar forming the inclosing frame of the screen, mitered preparatory to welding the mitered 25 portions together to form a corner of the screen frame.

Figure 8 is a fragmentary perspective view of the bar shown in the preceding view, with its mitered portion welded together to 30 form a corner of the screen frame.

Figure 9 is a cross-sectional view through 35 the screen frame, indicating at the left hand side, the screen wire as it is forced into the groove of the frame by a manually operated tool, and at the right-hand side, a flat wire or locking bar inserted in said groove over 40 the screen wire to secure the screen wire against dislodgement,—also the means employed to trim away the exposed marginal edge of the screen wire following the insertion of the locking bar.

Figure 10 is a similar cross-sectional view showing the screen under tension and secured 45 in the grooves by locking bars,—also overlapping burrs,—formed by the use of a cold chisel upon the wall of the frame adjacent the groove that it may overlap at intervals the locking bar.

Figure 11 is a cross-sectional view of the screen frame shown in Figure 2, taken on or 50 about line 11—11 of Figure 2,—showing a suitable tool inserted in one of the holes opening into the channel groove for driving out the locking bar.

Figure 12 is a fragmentary perspective view of the screen frame showing the upper transverse member off-set to receive one of the hook-shaped supporting brackets attached to the window casing, that the screen 60 frame may be contiguous with the surface of the window casing.

Figure 13 is a perspective view of one of the locking latches pivoted to the frame.

Figure 14 is a fragmentary elevation of 65 a screen frame with a fillet welded to its

round corner to close the opening between the corner and the window casing.

Referring now to the letters of reference spread upon the drawings:

A indicates the outer wall of a building, 70 B a window casing, C a lower sash frame, and D the upper sash frame, separated by a parting strip E, as commonly employed.

F indicates the usual window stool and 75 the window sill.

H denotes the frame of the window screen, of channel bar construction in cross-section, with a flange H¹ projecting from its outer walls, adapted to overlap the face of the window casing. The channel bar may be punched with a V-shaped notch, see Figure 80 5, that it may be bent at right angles to form a corner of the frame, as shown in Figure 6, the abutting surfaces of the notched portion being spot welded, if desired.

The bar however may be mitered as shown in Figure 7, and the mitered ends welded together, as indicated in Figure 8. When the bar is bent as shown in Figure 6,—forming a rounded corner,—a right-angle fillet piece H² is welded to the screen frame to close the opening, between the round corner of the frame and the wall forming the window opening.

In place of a metal fillet piece, welded to the frame, the opening may be closed by a wooden or other in-set, not shown.

I denotes the screen wire which in constructing the window screen is laid upon the frame with the marginal edges of the screen wire overlapping the grooves J in the frame of the screen.

A suitable manually operated tool K having a roller K¹ is now employed to push the screen wire into the groove as indicated in Figure 9, the roller being manually forced to traverse the screen wire under sufficient pressure to crowd the screen wire into the groove and against its lower wall.

A flat locking wire or bar L preferably formed with rounded corners is then inserted in the groove over the wire screen and driven into the groove until the upper surface of the locking bar is below or substantially flush with the face of the frame.

To secure the locking bar L against displacement, a cold chisel, nail-set or other suitable tool is then employed to off-set the wall forming the groove in the frame so as to overlap (h) the locking bar at spaced intervals.

The operation just described is repeated until the four marginal edges of the screen wire are lodged in the respective grooves of the frame and secured therein by the flat locking wires or bar. The projecting marginal edge of the screen wire is now cut off adjacent to the outer surface of the locking bar by a manually operated rotary cutting tool M, the cutting edge of the tool traversing 125 130

the screen wire adjacent to the locking wire, as indicated in Figure 9.

5 N is a reinforcing brace bar extending transversely across the frame and welded or otherwise secured to the side rails. N^a is a strip of metal overlapping the screen wire and the brace bar, to which it is secured by bolts N^b.

10 The upper bar of the frame is slotted to receive a pair of hooks P P secured to the window casing and to insure a tight joint between the frame and window casing, the frame is slightly off-set above the slotted portions to receive the shank of the hooks, as indicated at H^b in Figure 12.

15 In order that the wire screen may be readily removed from the frame when necessary to replace same with a new screen, holes J^a extending from the back of the frame—see Figure 11—into the grooves J are provided. To remove the wire screen I and the locking bar L from the grooves, a nail set or other suitable tool is inserted in the holes J^a that it may bear upon the screen and locking bar;—20 the nail set is then given a sharp blow with a hammer, thereby dislodging the screen and locking bar from the groove.

25 To secure the lower ends of the screen frames in the window casings, a pair of levers R, R are respectively pivoted to the side rails of the frame, having a cam-shaped knife edge R¹, which upon actuating the lever is adapted to force its entrance into the wood casing,—thus securing the frames against rattling or flapping. If metallic window casings are employed, the wall of the casing is 30 indented to receive the edge of the lever.

35 If a "half screen" is employed as shown in Figure 4 of the drawings, the frame is supported in a pair of channel members S nailed to the opposing walls of the window casing. To close the opening at the top of the "half screen" between the screen and the lower rail D¹ of the upper sash frame, an angle plate H² 40 is welded or otherwise secured to the upper rail of the screen frame,—its projecting flange extending toward the upper sash rail, thereby closing the opening between the screen and sash frames without interfering with either 45 when raised or lowered.

50 Having thus described our invention, what we claim is:

55 1. In a window screen, a frame comprising a metallic channel member having a flange integral with its wall extending outwardly from the channel portion, whereby it may overlap the face of a window casing to close the opening between the channel wall of the screen frame and the window casing, said flange punched to provide slots in spaced relation to each other, the wall of said flange above said slots being indented to overlap the shank of supporting hooks, whereby the frame may be in contiguous overlapping 60 relation to the window casing; and a plu-

rality of supporting hooks adapted to be secured to said window casing to support said frame.

2. In a window screen, a frame comprising a metallic channel member having a flange integral with its wall extending outwardly from the channel portion; a wire screen bridging the opening bounded by the screen frame, the marginal edges of the wire screen being lodged in the channel; a locking bar 70 lodged in the channel over the marginal edges of the wire screen, the walls of the channel member being burred to overlap the locking bar to secure the latter against accidental dislodgment. 75

80 3. A window screen comprising a metallic channel member, mitered, and bent at the miters, with the mitered portions welded together to form a rectangular frame, said channel member having a flange integral with its wall extending outwardly from the channel portion, whereby it may overlap the face of a window casing to close the opening between the channel wall of the screen frame and the window casing; a wire screen bridging the opening bounded by said frame, its marginal edges being lodged in the channel groove; and a locking member lodged in the channel groove over the marginal edges of the wire screen to secure said wire screen in 85 the frame, with the walls of the channel member burred to overlap the locking bar. 90

95 4. A window screen comprising a metallic channel member notched and bent at said respective notched portions to form a rectangular frame, with the abutting notched portions welded together, and a right angle fillet member welded to the respective corners of the screen frame, to form a sharp corner, 100 whereby the opening at the corners of the frame and the window casing may be closed; a wire screen bridging the opening bounded by the screen frame, its marginal edges lodged in the channel groove of the frame; and a locking member lodged in the channel groove of the frame over the marginal edges of the wire screen to secure said wire screen in 105 the frame. 110

115 In testimony whereof, we sign this specification.
